WINDOW CONSTRUCTION

Eugene C. Bingham, Easton, Pa.

Application January 16, 1935, Serial No. 2,005

9 Claims. (Cl. 20—40)

My invention relates to window construction and particularly to the mounting of windows in such a manner that when adjacent windows are raised, a clear unobstructed space is left below the adjacent windows or series of windows.

Heretofore, when windows have been mounted in frames the frame has extended throughout the height of the window so that there is a frame element between each pair of adjacent windows. 10 When the windows are raised, these frame elements form a series of spacing posts separated by the width of the window sash. These posts form obstructions which are in many cases undesirable. For example, in hoods for laboratory 15 desks a series of such posts separated only by the widths of the window interferes with the ease of manipulating or handling apparatus in the hood.

In my present invention, I provide a mounting 20 construction for windows in which each window may be raised or lowered and guided, but which does not have any obstructing posts or guides below the lifted windows.

In my invention, each window sash is provided with upwardly extending guide arms, one 25 at each side of the sash, which are guided in guides that extend upwardly from about the top of the window in its lowermost position. When the window is in its lowermost position, 30 the upwardly extending guide arms engage the guides for a considerable distance above the window and hold it rigidly in place. As the windows are raised or lowered the guide arms slide in the guides above the window space and serve 35 to guide and hold the windows in position. The edges of the window sashes overlap the guides so that the adjacent edges of the windows will contact and thus form a continuous wall when all of the windows are lowered. When the windows 40 are raised the lower edge of the windows are approximately even with the lowermost ends of the guides and the space below the windows is unobstructed. In case adjacent windows are 45 at a right angle to form a corner, the guide construction avoids the necessity for a corner post below the raised windows.

The various features of the invention are illustrated in the accompanying drawings, in which:—

50 Fig. 1 is a perspective view of a laboratory desk or hood, having a window frame and sash construction embodying the invention; Fig. 2 is a front view of the hood shown in Fig. 1; Fig. 3 is a horizontal section taken on the line 55 3—3 of Fig. 2; Figs. 4 and 5 are respectively end

elevations and vertical sections through the hood; Fig. 6 is a section on the line 6—6 of Fig. 4; Fig. 7 is a perspective view of another embodiment of the invention; Fig. 8 is a part plan view of the embodiment shown in Fig. 7; and Fig. 9 is a vertical section taken on line 9—9 of Fig. 7.

In the accompanying drawings, the invention is shown as applied to a laboratory hood having a desk 10 on the surface of which chemical or other apparatus may be set up and manipulated and having an inclined roof or hood 11. A flue 12 is provided at the back of the desk through which gases may be withdrawn and passed to an outlet 13 as indicated by the arrows in Fig. 5. 15 A series of windows 14 are provided to close the front and sides of the space above the laboratory desk. These windows 14 are each provided at their side edges with upwardly projecting guide arms 15, which slide vertically in guides 16 supported by suitable framework 17 above the top of the hood, attached in turn to wall or ceiling.

The side edges of the guides 16 are grooved as at 18 and 19, Fig. 3, to receive guide elements or keys 20 and 21 respectively, secured to the 25 inner faces of the windows 14, so that the windows are guided securely by the guides 16. The side edges of the windows 14 overlap the front faces of the guides 16 and abut the edges of adjacent windows as indicated at 22, Fig. 3, so that 30 when the windows are lowered below the lower ends of the guides 16, they form a substantially continuous, unbroken, partition.

If the guide 16 is arranged between a pair of windows 14 at right angles to form a corner, the 35 inner faces of the guide 16 are grooved and the guide or tongues 20 and 21 of the guide arm, slide in the grooves of faces at right angles. The edges of the window sashes in such a corner construction extend over the full width of the outside 40 faces and somewhat beyond, so that the edge of one window sash overlaps that of the other. The overlapping edge may be provided with a vertical groove 23 to receive a guiding feather 24 of the overlapped window and thus interlock these two 45 windows when in their lowermost position to form a firm, closed corner construction.

The window sashes may be counter-weighted by means of sash weights 25 suspended from a cord 26 that passes over pulleys 27 in the supporting frame 17 and thence downwardly to the upper edges of their respective sashes.

In the embodiment illustrated in Fig. 7, a laboratory desk or table is shown, that is free on all sides, but which may be entirely enclosed by win- 55

dows mounted by my invention. In this embodiment, four guides 28 are provided one above each corner of the desk or table, and having grooves similar to those of the guide 16 shown in Fig. 6. 5
5 The window sash in this construction is also provided with the tongue and groove construction shown in Fig. 6. Each of the guides 28 are additionally strengthened by a right angle shield 29 of metal secured at its upper end to the ceiling 10 and extending downwardly to approximately the lower ends of the guides. The shields 29 are pressed at their lower ends by connecting bars or rods 30. In this embodiment the windows are counter-balanced by sash weights 31 at one side 15 of the apparatus and connected to the sash weights by cords 32 drawn about guide pulleys 33.

While the invention has been described specifically for use on laboratory hoods or hooded 20 spaces above a working desk or table, it may be used generally wherever it is desirable to maintain a clear space free from posts or obstructions.

What I claim is:—

25 1. A window comprising a sash having guide arms, one at each side thereof, projecting above the upper edge of the sash, a frame having guides projecting downwardly and terminating above the bottom of said window sash when the latter 30 is in its lowermost position, said window sash and upwardly projecting guide arms overlapping the front surface of said frame guide and tongues mounted on said guide arms and said window sash extending into vertical grooves of said frame 35 guide.

2. A window comprising a window sash, each having a pair of guide arms, one at each side thereof, projecting upwardly above the upper edge of the sash, guide posts extending downwardly to engage said guide arms in all positions of said window, said guide arms overlapping the front faces, of said posts, a pair of said sashes being arranged at right angles and having the edge of one of said windows overlapping the 45 edge of the other.

3. A window comprising a pair of sashes arranged at a right angle and having the edge of one window grooved and the other tongued to engage said groove, a guide post within the angle 50 of said windows and terminating above the window space and guide arms extending above the upper edges of said windows and having tongues engaging grooves in said posts.

4. A work table, guide posts extending downwardly and terminating above said table to form a free space thereon, window sash slidable between said guide posts and having upwardly extending guide arms to engage said guide when the windows are lowered below the lower ends 60 thereof whereby said table may be unobstructed from all sides or may be entirely enclosed and hooded.

5. A work table, guide posts extending downwardly and terminating above said table to form 65 a free space thereon, window sash slidable be-

tween said guide posts and having upwardly extending guide arms to engage said guide when the windows are lowered below the lower ends thereof whereby said table may be unobstructed from all sides or may be entirely enclosed and hooded, and counter-weights or springs for said windows. 5

6. A table, guide posts projecting downwardly and terminating above the surface of said table to form a clear space, window sash guided between 10 said posts and having upwardly extending guide arms, said guide arms having tongues to engage grooves in said posts when said windows are lowered below the lower ends of said posts, said posts and windows being arranged to 15 form a complete enclosure above said table or to leave said table unobstructed from all sides.

7. A table, guide posts projecting downwardly and terminating above the surface of said table to form a clear space, window sash guided between 20 said posts and having upwardly extending guide arms, said guide arms having tongues to engage grooves in said posts when said windows are lowered below the lower ends of said posts, said posts and windows being arranged in 25 rectangular formation with corner sash arranged at right angles and having their edges overlapping the corner posts and engaging in a tongue and groove engagement, whereby the surface of said table may be entirely enclosed or may be 30 clear and unobstructed from all sides.

8. A table, guide posts projecting downwardly and terminating above the surface of said table to form a clear space, window sash guided between 35 said posts and having upwardly extending guide arms, said guide arms having tongues to engage grooves in said posts when said windows are lowered below the lower ends of said posts, said posts and windows being arranged in rectangular formation with corner sash arranged 40 at right angles and having their edges overlapping the corner posts and engaging in a tongue and groove engagement whereby the surface of said table may be entirely enclosed or may be 45 clear and unobstructed from all sides, and corner plates covering the edges of said corner sash.

9. A table, guide posts projecting downwardly and terminating above the surface of said table to form a clear space, window sash guided between 50 said posts and having upwardly extending guide arms, said guide arms having tongues to engage grooves in said posts when said windows are lowered below the lower ends of said posts, said posts and windows being arranged in rectangular formation with corner sash arranged 55 at right angles and having their edges overlapping the corner posts and engaging in a tongue and groove engagement whereby the surface of said table may be entirely enclosed or may be 60 clear and unobstructed from all sides, corner plates covering the edges of said corner sash, and presses for the lower edges of said cover plates.

EUGENE C. BINGHAM.
